(Model.)

M. W. LYNCH.

BUCKLE.

No. 247,507.

Patented Sept. 27, 1881.

Attest,
W. H. Knight,
Fred. D. Lynch.

Inventor,
Matthew W. Lynch,
by Will. T. Church,
His Atty.

UNITED STATES PATENT OFFICE.

MATTHEW W. LYNCH, OF MADISON, WISCONSIN.

BUCKLE.

SPECIFICATION forming part of Letters Patent No. 247,507, dated September 27, 1881.

Application filed February 24, 1881. (Model.)

To all whom it may concern:

Be it known that I, MATTHEW W. LYNCH, of Madison, in the county of Dane and State of Wisconsin, have invented certain new and useful Improvements in Buckles; and I do hereby declare the following to be a full, clear, and exact description of the same, reference being had to the accompanying drawings, forming part of this specification, in which—

10. Figure 1 is a perspective view of the invention; Fig. 2, a top-plan view of the same; Fig. 3, a longitudinal section taken on the line *xx*, Fig. 2; Fig. 4, a bottom view, with the casing broken away to show the construction of the lock. Fig. 5 is a top-plan view, and Fig. 6 a longitudinal sectional view, of a modification of the invention; and Fig. 7, a view of the tongue of the buckle shown in Figs. 5 and 6.

15. Similar letters of reference in the several figures denote the same parts.

My invention has for its object to provide an improved buckle the tongue of which can be securely locked, when desired, by means of a locking mechanism arranged within the buckle, 20 whereby to prevent the detachment of the strap accidentally or otherwise than by the application of the key of the locking mechanism.

To this end the invention consists in certain novelties of construction and combination of 25 parts, which I will now proceed to describe, and which will be pointed out particularly in the claims.

In the drawings, A represents the body or main plate of the buckle, cast or otherwise 30 formed of metal, preferably brass, and provided with side flanges, B B, as shown. Between these side flanges is pivoted, by means of a bolt, c, a metal plate, C, carrying the prong or tongue c'. This plate is preferably wedge-shaped, and its pivotal bolt passes through its 35 thickest edge. Shoulders c³ are formed on the bolt c inside of the flanges, and the ends of the bolt are riveted down on the outside of the flanges, thus making a very strong and secure 40 connection, and causing the bolt to materially assist in supporting the flanges against both inward and outward pressure.

The body or main plate A is provided with a vertical slot or opening, a, and with a lateral 45 slot, a', intersecting said slot a at one end, as

shown. Within the slot a' a bar or bolt, D, is arranged. This bolt, when moved in one direction, closes one end of the slot a; but when moved in the opposite direction, a recess or notch, d, in its side is brought opposite the slot a, leaving the latter open throughout its entire length. When the slot a is thus left open and the plate C is turned down the tongue c' enters the slot and swings up against the end wall, a², thereof. The bolt being then 60 moved so as to cause its solid portion to fill the opposite end of the slot, the tongue is confined within the slot, and is prevented from being released until the bolt is again moved. One side or wall, d', of the recess d in the bolt 65 is slightly raised above the top face of the bolt, in order that when the bolt is moved to close the end of the slot such raised portion will strike against the opposite wall of the slot a, and thus positively arrest the movement of the 70 bolt; and to prevent the said raised portion from projecting into the slot a when the recess and said slot are made to correspond or register, the wall of the slot is recessed at a³ for its accommodation, as shown.

75. The bolt D is provided with a longitudinal slot or channel, d³, into which leads a series of lateral slots or channels, d⁴—preferably three or more in number—containing pins d⁵, shorter than said slots or channels, and within the body 80 or main plate A are arranged a series of slots or cavities, a⁴, corresponding in number to the number of lateral slots in the bolt, and containing pins a⁵ and spiral springs a⁶ for pressing the pins outward. When the bolt is so positioned as to confine the tongue of the buckle within the slot a the pins a⁵ register with the slots in the bolt, and are forced by their springs 85 into said slots, against the short pins d⁵ therein, and effectually lock the bolt from longitudinal movement. The bolt is released from the spring-seated pins by means of a key, K, which is so shaped that when inserted in the longitudinal slot or channel d³ of the bolt it will press outward the pins d⁵ and cause them, in 90 turn, to press back the pins a⁵ until they are on a line with the edge of the bolt. A forward pressure of the key then causes the bolt to move longitudinally forward, so as to bring its recess opposite the slot a and enable the tongue 95

to be released. During the forward movement of the bolt the spring-seated pins bear against its solid edge. To lock the bolt again it is only necessary to remove the key and push back the bolt by pressing on its projecting end, and when its lateral slots come opposite the spring-seated pins they will again be projected into the same, as before.

5 The small pins d^5 in the bolt should be of unequal length, and the key so formed with projections and depressions that when fully entered all the pins will be properly aligned.

10 The buckle is intended to be attached to its strap by riveting the end of its body thereto, as shown, or by slotting it for the passage of the strap, or by forming a bar upon it for the attachment of the strap.

15 Figs. 5 and 6 show the invention applied to a different form of buckle, A representing the body of the buckle, constructed preferably of a casting of brass, with sides B' and cross-bars C' of rolled brass; D', a tongue, pivoted within a slot, s' , of the body; and E', the sliding bolt, adapted to engage with a projection or spur, f' , on the inner end of the tongue, for the purpose of keeping the tongue locked. The tongue is preferably mounted upon a pivot or stud, cast with or otherwise attached to the body A, within the slot, and is applied to said 20 pivot by slitting it from its perforation outward, as shown, and, after application, closing the parts together and, if necessary, brazing them. The bolt in this form of buckle is entirely within the body, and does not project out beyond the body in any of its movements, as in the form of buckle shown in Fig. 1, and the same locking and unlocking arrangement is preferably employed, except that to lock, instead of pressing upon the end of the bolt, a 25 stud, h' , projecting from the bolt through a slot, i' , in the body, is caught hold of and moved.

30 Instead of a longitudinally-sliding bolt for engaging with the tongue to lock it, a revolving locking-cylinder with a locking-projection may be employed, locking-pins being arranged within said cylinder and operated by a key thrust within the cylinder. I, however, prefer the sliding-bolt arrangement.

35 5. I claim as my invention—

1. The combination of the hinged or pivoted tongue, the body or main plate having the slot for the reception of the tongue when swung down, and a movable bolt or bar adapted to

close one end of the slot to confine the tongue, substantially as described. 55

2. The combination of the hinged or pivoted tongue, the body or main plate having the slot for the reception of the tongue when swung down, and a movable bolt or bar adapted to close one end of the slot to confine the tongue, and means for permanently locking said bolt, substantially as described.

3. The combination of the hinged or pivoted tongue, the body or main plate having the slot for receiving the end of the tongue when swung down, and the longitudinally-moving bolt or bar D, having the recess in its side, whereby said bar when moved in one direction admits the tongue into the slot, and when moved in the opposite direction prevents said tongue from being withdrawn from the slot, substantially as described. 70

4. The combination of the body or main plate of the buckle, having the slot for accommodating the end of the pivoted tongue, and the longitudinally-moving locking bolt or bar having the recess in its side, whereby said bar when in one position admits the tongue into the slot, and in another position prevents said tongue from being withdrawn from the slot, substantially as described. 75

5. The combination of the body or main plate having the slot a therein for the accommodation of the end of the tongue with the longitudinally-moving locking-bolt having the recess in its side, and one wall of which is raised to form a stop to positively arrest the forward movement of the bolt, substantially as described. 80

6. The combination of the longitudinally-moving locking-bar, having the raised wall to its side recess, with the body or main plate slotted for the accommodation of the end of the tongue, and having the recess a^3 for the accommodation of the raised part of the bolt, substantially as described, for the purpose specified. 85

7. The combination of the slotted inner body or main plate, the hinged plate carrying the tongue, the locking-bar having the longitudinal slot and lateral slots and pins, and the spring-seated pins working in cavities in the body or main plate, substantially as described. 90
